(57) **CLAIM**

The ornamental design for a foot support wrap, as shown and described.

DESCRIPTION

FIG. 1 is a top plan view of a foot support wrap;

FIG. 2 is a front elevational view thereof;

FIG. 3 is a bottom view thereof;

FIG. 4 is a left side elevational view thereof, the right side elevational view being a mirror image thereof;

FIG. 5 is a rear elevational view thereof;

FIG. 6 is an isometric view thereof, showing the foot support conformed to a human foot shape with the support wrapped around the foot and ankle; and,

FIG. 7 is a second isometric view thereof, showing the foot support conformed to a human foot shape with the support wrapped around the foot and ankle.

The broken lines illustrate environmental structure and form no part of the claimed design.
